UNITED STATES PATENT OFFICE.

GEORGE W. MULLER, OF WASHINGTON, DISTRICT OF COLUMBIA.

RAILWAY-RAIL JOINT BAR.

Application filed August 20, 1928. Serial No. 300,308.

This invention relates to joint bar plates or fishplates, used for holding the meeting ends of two railway rails against separation or displacement, and to keep the ends of the 5 rails permanently up to a desired level and in a straight line.

The principal object of this invention is the production of joint bar plates of composite and special construction, found to be 10 particularly effective for lifting the rail joint up and for holding the meeting ends of railway rails in lasting positions after they are laid down, and which will not work 15 loose and give a rebound or reflex action at the joint as the wheel loads pass over the rails.

In this instant invention the joint bar is made up of two separable members fitting together as hereinafter described, one of the 20 pieces being shorter than the other. The shorter piece is fashioned to fit against the web of a rail in contact with the under side or ball part of the rail, and upon the top of the rail base. The longer member is made 25 to project beyond the ends of the shorter member and to be placed upon the outer surface of the shorter member, and to rest on top of the base of the rail. Such longer and shorter members are arranged upon oppo- 30 site sides of the meeting ends of the rails, and they are secured by bolts passing through the members and through the rails.

It is an object of this invention to form the shorter member to fit the side of the rail 35 from the ball to the base or flange, and to follow the curve of the side of the web of the rail which is thinnest at its middle longitudinal line and gradually thickens towards the ball and base. The shorter member 40 is substantially of wedge-shape as illustrated and described herein, and the pounding of the wheel loads passing over the joint of the rails drives the rail ends and the wedge-like shorter member downwardly 45 with the effect of tightening the grip of the bolts.

It is also an object of this invention to make the longer member of this invention 50 of spring steel, in order that it may possess considerable elasticity when bent flatwise or edgewise. When the ends of the longer member which extend beyond the ends of the shorter member are drawn towards each other by the bolts passing through the rails,

the whole joint fastening is under constant tension and all parts are held firmly yet in a degree yieldingly up to level and in a straight track line.

A number of modifications of this invention are shown in the accompanying drawings, 55 and it will be understood that these particular conformations are in no wise intended to represent all the configurations that may be given the members of this invention, but are merely illustrative of advantageous constructions. This invention is not limited to any selected size or shape of the members or 60 to the number of bolts or the positions thereof, as various changes of such adjuncts will readily suggest themselves to those familiar 65 with railway appurtenances and track construction.

Of the drawings Figure 1 represents a vertical section through a railway rail equipped 70 with this invention.

Figure 2 is a vertical section similar to that set out in Figure 1, showing a modification of the contacting surfaces of the inner and shorter and outer and longer members.

Figure 3 is a side view of the meeting of 75 two railway rails having this invention in position to secure the joint, and showing one location of the bolt holes.

Figure 4 is a vertical section of a rail secured by a compound joint bar plate fashioned in accordance with another modification of this invention, the contacting faces of the two members on both sides of the rail being serrated.

Figure 5 represents a section of an arrangement of the parts of this invention as 80 illustrated in Figure 1, and shows a modified and recessed form of the contacting surfaces of the compounded members.

Figure 6 sets forth a vertical cross section 85 of a rail with a modified form of this invention applied thereto, and secured by a bolt, lock washer and nut of customary nature. In this figure the contacting surfaces of the two members are curved, but the wedge-form 90 character of the inner and shorter member is preserved.

Figure 7 is a similar view to Figure 6 with the inner or wedge member omitted.

Figure 8 represents a longitudinal section 105 of the web of a rail joint showing the joint bar plate members constructed in accordance with invention in section lengthwise. The

positions of the bolt holes are exhibited in this figure with conically enlarged or expanded mouths provided for certain of the bolt holes.

5 Figure 9 is a face view of the outer side of one of the longer members.

Figure 10 is an inside surface view of a longer member.

10 Figure 11 is an outer face view of a shorter member.

Throughout the drawings and description, the same number is used to refer to the same part.

Considering the drawings, Figures 1 and 15 3, it will be noted that the rail shown for the purposes of this explanation has the head or ball designated by numeral 1, the web or vertical part 2, and the base 3, having upper 20 outwardly and downwardly slanting surfaces marked 4 and 5. It will be observed that the web 2 is thinnest in the middle and expands or thickens gradually upwardly to the head 1 and downwardly to the base 3, and that the member 6 of this invention arranged 25 in contact with the web 2 fits the contour of the web, the lower part of the ball of the rail and the portion of the upper surface 4 of the base of the rail next to the web. It will further be seen that the outer face or surface 7 30 of the member 6 is not vertical, but inclines inwardly and downwardly, which gives to the member 6 a distinct wedge shape. In contact with the member 6 is disposed the outer member 8, the top of which is slightly below 35 the ball of the rail, and its inner face or surface 9 corresponds in slant and lies in contact with the outer face 7 of the member 6. The lower end of the member 8, marked 10 has the same inclination and rests upon the 40 surface 4 of the base of the rail.

In Figure 3 two railway rails 11 and 12 meet, and this invention is applied thereto. It is now shown that the outer member 8 is the longer and that it extends at the ends beyond 45 the ends of the inner member 6 which is the shorter member. It is held within the purview of this invention to locate three bolt holes 13, 14 and 15 as illustrated in Figure 3, the middle hole 14 being slightly higher from the rail base and passing between the ends of the meeting rails. The invention, however, is not limited to that disposition of the bolt holes.

55 A great variety of shapes may be readily devised for this invention, but the wedge-like form of the shorter plate or member and its wedge action under the wheel loads is retained.

60 As set forth in Figure 2, the modified form of this invention comprises the rail 16, the inner member 17 fitting the web, ball and base of the rail as before, and arranged in contact with an outer and keeper member 18 as explained. But the contacting surfaces of the 65 inner and shorter member 17 and the outer

and longer member 18, designated 19, 20, 21, 22 and 23 for the shorter member, have corresponding inclines for the contacting surface of the outer member 18. Nevertheless, the wedge-formed shape of the inner member 17 70 is preserved. The same is true of the modified constructions set forth in the Figures 4 and 5. In Figure 4 the rail 24 has immediately against it the inner member 25 fashioned with a serrated outer surface 26, and the outer member 27 has a like surface contacting with the inner member. In Figure 5, the rail 28 has against its web, ball and base the inner member 29, provided with an outer surface having recesses 30 and in contact with a corresponding surface provided on the outer member 31. 75 80

85 In Figure 6 the rail 32 has against it the inner and shorter member 33, the outer surface of which is curved on a relatively long or predetermined radius. This curved surface designated by number 34 engages a correspondingly curved surface 35 of the outer and longer member 36. It will be noted that the inner member 33 is thickest at the top and 90 that its wedge-like cross section is preserved. A bolt 37, provided with the usual spring washer 38 and nut 39 is shown passing through the members and web of the rail in Figure 6. 95

100 Figure 7 illustrates the same parts as were set out in Figure 6 with the inner member 33 omitted, to show the wedge-like seat or space which the inner member occupies. This figure may also be taken to represent a section vertically through the ends of the longer member beyond the ends of the shorter member, and this figure will be again referred to.

105 Figure 8 is a section longitudinally through the webs of meeting rail ends 40 and 41, showing the shorter member 42 and longer member 43 on one side of the rail joint, and the shorter member 44 and longer member 45 on the other side. The locations of the bolt holes 46 and 47 are also set out, and those holes may have expanding mouths, or, as illustrated in Figures 9 and 10 the bolt holes 47 of the longer member 43 may have mouths of elliptical shape. This invention is 110 in no way limited to the forms or locations of the bolts and bolt holes, and the bolts may or may not have expanded portions near their heads to engage the expanded bolt holes shown. 115

120 Figure 11 shows an outer face of a shorter member 48 made in accordance with this invention.

125 Either the longer or the shorter members of this invention as illustrated and described may be rolled from and in one piece by suitable set-up of rolls, and then cut into proper lengths.

Regarding the operation of this invention in its modified forms as well as in its preferred or first design, Figure 7 may be con- 130

sidered in connection with Figure 1. Suppose the bolt 37 in Figure 7 has its counterpart in Figure 1 drawing the ends of the outer members towards each other beyond the ends of the shorter members. It is believed to be clear that the lower face or surface 10 of the longer member 8 will tend to slide upwardly towards the web of the rail as the bolts are tightened. In other words, the 10 tighter the bolts, the greater will be the lifting effect upon the shorter and inner plate and upon the under side of the balls of the rails at their meeting line. The effect of the wheel loads is to exert tension upon the bolts, 15 and the greater that tension may be the greater will be the lifting effect or resistance of the rail joint constructed in accordance with this invention.

The two piece rail joint bar constructed in 20 accordance with this invention can be made of any length, thickness or width, and the outer member may be of good grade of steel in order that it may possess as fully as may be desired elastic capacity both sidewise and 25 edgewise. Bars as described herein can be applied to and used on any rails, whether those rails be carried on ties of wood, metal or concrete, and upon any form of tie plate, but most advantageously upon the ties and tie 30 plate constructions devised by this applicant.

Having now described this invention and explained the manner of its use, I claim:—

1. Railway rail joint bars, each comprising two members one being longer than the other, 35 the shorter member being constructed for arrangement against the webs of meeting rails, the longer member being arranged outwardly against the shorter member and having ends extending beyond the shorter member and bearing upon the rail base.

2. Railway rail joint bars, each comprising two members one being longer than the other, the shorter member being constructed for arrangement against the webs of meeting rails, 45 the longer member being arranged outwardly against the shorter member and having ends extending beyond the ends of the shorter member, the said extended ends being elastic and bearing upon the rail base, and bolts 50 passing through the said extended ends of the longer member to draw them together under constant tension.

3. Railway rail joint bars, each comprising two members one being longer than the other, 55 the shorter member being constructed for arrangement against the webs of meeting rails, the longer member being arranged outwardly against the shorter member and having ends extending beyond the shorter member, the longer member having an inclined 60 lower surface resting upon the top of the rail base, and bolts for drawing the extended ends of the longer member towards each other whereby the said longer member is forced upwardly upon the base of the rail.

4. Railway rail joint bars, each comprising two members one being longer than the other, the shorter member being wedge-shaped in cross-section and constructed for arrangement against the webs of meeting rails, the 70 longer member being arranged outwardly against the shorter member and having ends extending beyond the shorter member, and bolts for securing the two members to the rail ends.

5. Railway rail joint bars, each comprising two members one being longer than the other, the shorter member being adapted for arrangement in contact with the under side of the ball of a rail, the longer member 80 being arranged outwardly against the shorter member and having ends extending beyond the shorter member and bearing upon the rail base, and bolts passing through the said members for securing them to the ends of meeting 85 rails.

6. Railway rail joint bars, each comprising two members one being longer than the other, the shorter member constructed for arrangement in contact with the under side of the ball of a rail and with the base of the rail, the longer member being adapted for arrangement outwardly against the shorter member and having ends extending beyond the shorter member and bearing upon the rail base, and 95 bolts passing through the said members for securing them to the ends of meeting rails.

7. Railway rail joint bars, each comprising two members one being longer than the other, 100 the shorter member adapted for arrangement with the under side of the ball of a rail, the longer member being arranged outwardly against the shorter member and having ends extending beyond the shorter member, bolts passing through said members for securing 105 them to the meeting ends of rails, and the said longer member having a slanting lower surface constructed to rest upon the upward slant of the top of a rail base whereby when said members are drawn together the shorter member is forced upward against the ball of the rail.

8. Railway rail joint bars, each comprising two members, one being longer than the other and having ends extending beyond the ends 110 of the shorter member, the said members having mutually contacting surfaces whereby an upward force applied to the longer member similarly impels the shorter member.

9. Railway rail joint bars, each comprising 115 two members, one being longer than the other and having ends extending beyond the ends of the shorter member, the said shorter member being of wedge-shape, and the said members having mutually contacting surfaces whereby an upward force applied to the longer member 125 is communicated to the shorter member.

10. Railway rail joint bars, each comprising two members, one being longer than the other and having ends extending beyond the 130

ends of the shorter member, the said members having mutually contacting interfitting surfaces whereby an upward force applied to the longer member is communicated to the shorter member.

11. Railway rail joint bars, each comprising two members, one being longer than the other and having ends extending beyond the ends of the shorter member, the said members having mutually contacting surfaces having differently inclined portions whereby an upward force applied to the longer member is communicated to the shorter member.

12. Railway rail joint bars, each comprising two members one being longer than the other and having ends extending beyond the ends of the shorter member, the said members having mutually contacting surfaces having a plurality of inclined portions whereby an upward force applied to the longer member is communicated to the shorter member.

13. Railway rail joint bars, each comprising two members, one being longer than the other and extending beyond the other, the said members having mutually contacting surfaces provided with a plurality of adjoining surfaces inclined in different directions.

14. The combination in a railway rail joint, of two rails aligned and having meeting ends, rail joint bars each comprising two members one longer than the other and extending endwise beyond the other, the shorter members being arranged against the opposite sides of the rails, the longer members being arranged outwardly against the shorter members and bearing at their ends on the said base, and bolts passing through the said members and rails for securing them together.

15. The combination in a railway rail joint, of two rails aligned and having meeting ends, rail joint bars each comprising two members one longer than the other and extending endwise beyond the other, the shorter members being arranged against the opposite sides of the rails and against the under side of the balls of the rails, the longer members being arranged outwardly against the shorter members and bearing at their ends on the said base, and bolts for securing the members to the ends of the rails.

16. The combination in a railway rail joint, of two rails aligned and having meeting ends, rail joint bars each comprising two members one longer than the other and extending endwise beyond the other, the shorter members being arranged against the opposite sides of the rails and against the balls of the rails and upon the tops of the bases of the rails, the longer members being arranged outwardly against the shorter members and bearing at their ends on the said base, and

bolts for securing the members to the ends of the rails.

17. The combination in a railway rail joint, of two rails aligned and having meeting ends, and bases constructed with upwardly inclined top surfaces, rail joint bars each comprising two members one longer than the other and extending beyond the other endwise, the shorter members being arranged against the sides of the rails, the longer members arranged outwardly against the shorter members and upon the inclined tops of the rail bases and bolts for securing the members and rails together thereby exerting a lifting force upon the said members.

18. The combination in a railway rail joint, of two rails aligned and having meeting ends and bases with upwardly inclined tops, rail joint bars each comprising two members one longer than the other and extending beyond the other, the shorter members being arranged upon the sides of the rails and against the under sides of the balls of the rails, the longer members being arranged outwardly against the shorter members and upon the said upwardly inclined tops of the rail bases, and bolts for securing the members and rails together whereby a lifting force is applied to the said members.

19. The combination in a railway rail joint, of two rails aligned and having meeting ends and bases with upwardly inclined tops, rail joint bars each comprising two members one longer than the other and extending beyond the other, the shorter members being arranged upon the sides of the rails and against the under sides of the balls of the rails and upon the bases of the rails, the longer members being arranged outwardly against the shorter members and upon the said upwardly inclined tops of the rail bases, and bolts for securing the members and rails together whereby a lifting force is applied to the said members.

20. The combination in a railway rail joint, of two rails aligned and having meeting ends and bases with upwardly inclined tops, rail joint bars each comprising two members one longer than the other and extending beyond the other, the shorter member having sides converging downwardly and arranged upon the sides of the rails and against the balls of the rails, the longer members being arranged outwardly against the shorter members and upon the said upwardly inclined tops of the rail bases, and bolts for securing the members and rails together whereby a lifting force is applied to the said members.

In testimony whereof I affix my signature.

GEORGE W. MULLER.
